UNITED STATES PATENT OFFICE.

LEONARD M. PHELPS, OF PHILADELPHIA, PENNSYLVANIA.

MEANS FOR AUTOMATICALLY CLOSING WINDOWS.

1,341,155.

Specification of Letters Patent.

Patented May 25, 1920.

Application filed November 1, 1916. Serial No. 128,976.

To all whom it may concern:

Be it known that I, LEONARD M. PHELPS, a citizen of the United States, residing at Philadelphia, in the county of Philadelphia 5 and State of Pennsylvania, have invented certain new and useful Improvements in Means for Automatically Closing Windows, of which the following is a specification, reference being had to the accompanying 10 drawings.

This invention relates to windows, and particularly to latches designed to hold the window sashes open, but so constructed as to permit the latches to be automatically released and the windows closed under certain conditions.

The general object is to provide latches of this character which will permit the ordinary and usual manipulation of the windows to close or open them.

Still another object is to provide latches and latch releasing mechanism of this character so constructed that the latch releasing mechanism may be connected up with a 25 number of different automatic actuating means constructed so as to actuate the latch releasing mechanism under various conditions.

A further object is to provide a device of 30 this character which is very simple, cheaply constructed, and readily applied.

Other objects will appear in the course of the following description.

My invention is illustrated in the accompanying drawings, wherein—

Figure 1 is a diagrammatic view illustrating a plurality of windows and means whereby the latches of the windows may be released to permit the windows to close under certain conditions, all the parts being in elevation except the water receptacle which is partly in section, the casings for the electrically operated closing means, the electrical releasing mechanism, and the vessel for containing mercury, these parts being shown in section;

Fig. 2 is a fragmentary perspective view of a window showing the means whereby the windows are urged to a closing position and 50 the latches for holding the upper and lower sashes;

Fig. 3 is a transverse section through the rails of two sashes and through the spring actuated roller 10;

55 Fig. 4 is a horizontal sectional view through the wall of a house, the window

casing and the window sashes showing my invention as applied between the walls of the house and illustrating a modified form of latch;

Fig. 5 is an elevation showing another form of strain applying lever with its connected latch operating rods;

Fig. 6 is a fragmentary vertical sectional view through the window casing shown in 65 Fig. 4 showing one of the latches; and

Fig. 7 is a fragmentary elevation of a part of a window casing and the upper and lower sashes thereof and showing a slightly modified form of latch mechanism.

Referring particularly to Fig. 1 which illustrates my invention applied to a pair of lower windows and a pair of upper windows, it will be seen that the windows are of any ordinary or usual form, the windows 75 being identified by the letters A, B, C and D. Each window has the usual casing and the upper and lower sashes designated S and S' respectively. The upper rail of the lower sash in each of these windows is indicated as being provided with a spring actuated winding drum 10 over which a tape, cord or other flexible connection 11 passes and upon which this flexible connection is wound, this connection 11 extending down 85 to and being connected to the lower rail of the upper sash as at 12. I do not wish to limit myself to any particular construction of the spring roller. I have illustrated it, however, in Fig. 3, as a winding drum provided with an interior coiled spring. With 90 this construction, the upper sash is always urged toward its closed position and the lower sash is always urged toward its lowered position. It is not essential that this 95 spring actuated winding drum be used, as the balance weights of the window may be so arranged that the upper sash will be urged to its closed position and the lower sash urged to its lowered position. This 100 can be accomplished by increasing the weights for the upper sash and decreasing the weights for the lower sash so that the lower sash will more than counterbalance its weights and the upper sash will not counterbalance the weights connected to it. By 105 providing the spring roller, however, there is no necessity of changing the balance weights of the windows and this is particularly of value in windows of houses already 110 constructed.

The upper sash is provided with a plural-

ity of outwardly projecting pins 13, of any desired number, and arranged on one of the side bars of the upper sash, while the lower sash S' is provided at its lower corner with 5 the outwardly projecting pin 14. Operating in connection with the upper sash and its pins 13 is a pivoted latch 15, illustrated in detail in Fig. 2, whose head is notched to receive any one of the pins 13 and which has 10 an outwardly projecting shank 15^a. This latch, by means which will be hereafter described, has its head urged toward the longitudinal axis of the window so that it may be engaged with any one of the pins 13. 15 Operating in connection with the pin 14 of the lower sash is a vertically disposed latch bar 16 which extends parallel to the side bar of the lower sash, is pivotally supported upon brackets 17, and has an outwardly projecting arm 16^a or shank. The pin 14 is 20 adapted to engage in any one of the notches in the lower bar 16 while the single notch in the latch 15 is adapted to engage with any one of the pins 13. The reason for having 25 a single pin 14 on the lower sash, and a plurality of pins 13 on the upper sash, is to permit the windows to be brought down into register with each other, that is to permit the sashes to be brought down into register 30 with each other when desired and permit both the upper and the lower sashes to be adjusted to any desired degree of opening. In the construction shown in this Fig. 1, the latches are shown as disposed upon the 35 outside of the window. They may, however, be disposed upon the inside of the window or in the window casing and the actuating mechanism now to be described may be disposed within the wall of the building. 40 For the purpose of actuating these latches I provide for each pair of windows a member 18 pivotally supported between the windows. This member may have the form of the lever illustrated in Figs. 1 and 5 or as 45 illustrated in Fig. 4, it may be a straight lever 18^a perforated at its opposite ends. Connected to the perforation at one end of this lever 18 (or 18^a) are rods 19 and connected to the opposite perforation are a like 50 pair of rods 19^a. One of the rods 19 of a pair is connected to the arm or shank 15^a of the latch 15 while the other rod of the same pair is connected to the arm 18 and to the arm 16^a of the latch bar 16. These rods 19 55 are formed intermediate their length with the spring coils 20. These spring coils, when the rods 19 are drawn laterally, exert a spring tension on the projecting arms 15^a and 16^a of the latches 15 and 16 so as to 60 urge these latches into the path of the pins 13 and 14 respectively. When, however, the lever 18 is rotated upon its pivot in the direction of the arrow in Fig. 1, so as to release the strain upon the rods 19, the tension 65 of the springs 20 will be relaxed to such an

extent that the window sashes may be shifted by roller 10, the pins 13 and 14 simply slipping past the notches in the latches, and the sashes not being held by these latches. Preferably, though not necessarily, 70 each of the levers 18 is formed with a depending portion 21 having a curved face 22 and a flexible connection 23 is attached to the upper corner of the lever and operates over this curved face in the same manner 75 that a cord operates over a sector or pulley. It will be seen that when the flexible connection 23 is drawn downward that the lever will be turned in such position as to draw one pair of rods 19 in one direction and the 80 opposite pair of rods in an opposite direction until the point of connection between one pair of rods and the other pair of rods is nearly on a dead center. Each of the windows A, B, C and D is provided with 85 the latches, as described, and for each pair of windows there is one of the levers 18, as described. Lever 18 for windows C and D is connected by 23 to lever 18 for windows A and B while connection 23 from this lever 90 extends to a magnetic latching or locking device, designated generally E. As illustrated, this is disposed in a casing and comprises an angular lever 24, pivoted at 25, having an arm 26 and an arm 27 projecting 95 at right angles to the depending arm. The flexible connection 23 extends to and engages the arm 26 below pivot 25. The lever 24 when in operative position is on a dead center but is urged from this dead center by a 100 contact spring 24^a. Thus the friction of the arm 27 with the member 28 is reduced to a minimum and is due solely to the action of the spring 24^a. If lever 24 is off its center, then the strain of arm 27 on member 28 105 will be increased by an increase in the number of windows operated. The arm 27 is held in the position shown in Fig. 1 by a detent armature 28 retracted by spring 29 and attracted by electro-magnet 30. As an 110 additional means for shifting this detent 28 in case magnet 30 does not operate, I provide an operating lever 31 pivoted intermediate of its ends, bearing at its upper end against the lever 28 and at its lower end 115 being connected by a flexible connection 32 to certain means which will hereafter be described whereby it may be actuated, this connection 32 passing out through an opening in the wall of the casing. The electro- 120 magnet 30 is connected to a source of energy and in circuit with the various operating devices now to be described. 125 To release the latches in case of rain, I provide a casing 33 inclosing the lever 34, having a cup 35, an adjustable counterweight 36, and a pipe 37 leading from a collecting pan 38. Rain collecting in the pan trickles into the cup 35 and depresses lever 34, causing a contact member 39 to engage a contact 130

40 connected by wire 41 to one pole of battery 42, the lever 34 at its pivot being connected by wire 43 to the other pole of the battery 42 through magnet 30. Thus, when 5 the lever 34 descends, a circuit will be closed through battery 42, contact 40, lever 34, wire 43, wire 45^b, magnet 30, wire 45^a, lever 24 and contact 24^a, and thence by wire 45 back to the battery. The energizing of the electric 10 magnet 30 attracts detent 28, which is urged in one direction by spring 29 and lever 24 rotates to a position releasing strain on the connections 23, thus releasing the tension on springs 20 and on the latches. The latches thus become inoperative to hold the 15 sashes in their adjusted positions.

To cause the closing of the window in case of fog or heavy dew, I provide a lever 46 normally bearing against a stop 47 and connected by a fibrous cord to lever 34. When 20 damped, this fibrous connection will contract and draw down lever 34 and energize the magnet 30 and cause the closing of the window. The tension of the fibrous element 25 may be adjusted by screw 47.

In order to release the window latch at a predetermined time, I have shown spaced contacts 49 disposed in a shunt circuit between battery 42 and magnet 30 and disposed 30 between these contacts is the alarm winding key 51 of an alarm clock 50. When the alarm goes off, the alarm winding key will close the circuit between the two members 49 and, therefore, close the circuit 35 through the magnet 30.

To provide for closing the windows on a change in temperature, I provide a thermostatic control comprising a non-conductive base 52, having a slidably mounted plate 53, supporting a vessel 54, and having a bulb 55. In this vessel there is inserted a metallic plug 56 in contact with the mercury in the vessel. The vessel is held to the plates 53 by metallic bands 57 and 58. The plate 53 is 40 vertically slotted, at 59, so that the plate 53 may be vertically adjusted and with it the vessel 55. Contacts 60 and 61 engage with the cross bar 57. When the vessel with the cross bar 57 is moved up, the cross bar will 45 engage contact 61. When it is moved down, it will engage the contact 60. A metallic rod 62 passes through guides 64 and into the top of the vessel, one of these guides having a set screw 65 to hold the rod. A spring 66 urges the rod downward into the vessel. Mounted on the base is a pivoted pointer 67 operating on a scale 68, a flexible connection 69 connecting the pointer to the rod 62. By turning the pointer 67 in one direction, the rod will be raised, and in the opposite direction, the rod will be lowered. A metallic plug 56 is electrically connected to the cross bar 57 by means of a wire 70^a. From contact 61 extends a wire 71 leading 55 to switch 72, then to one pole of the battery 73, and from the other pole of the battery a wire 74 leads through an electro-magnet 75 to wire 44, leading from the battery 42. This wire 44 extends to the metallic strap 64 and thence to the wire 43 connected to 70 the wire 45^b.

If it be desired that the window shall close in case the temperature is lowered below a predetermined point, the vessel 55 is shifted upward so that the cross bar 57 is in engagement with the contact 61. This brings the rod 62 down into the mercury, the rod 62 having been previously adjusted by shifting pointer 67 to the proper degree of temperature on the scale 68. This closes the 80 circuit through magnet 75. When the mercury drops, it lifts rod 46. This breaks the circuit through battery 73 and magnet 75 and causes the release of an armature 77 which shifts into engagement with the contact 78 connected through a wire 70^b to battery 42. Thus, a circuit is completed through the magnet 30, withdrawing the armature 28 from its engagement with the member 24 and permitting the windows to 90 close. Other adjustments may be made to permit the windows to close when the sun strikes into the window too strongly. The switch 72 permits the local circuit, including battery 73 and magnet 75, to be cut out 95 when it is not desired.

It is also possible to cause the release and consequent closing of a number of windows by the closing of one window. Thus, for instance, the window F, which is representative of a number of windows, is normally held open by the latching mechanism previously described, the lever 18 and the rods 19. From the lever 18 extends a flexible connection 23^a which at its lower end is connected to a bell crank lever 96. This bell crank lever is connected to a longitudinally shiftable rod 97 urged in one direction by a spring 98. At its opposite end the rod 97 is flexibly connected, as by a pivoted link 100, to the short end of a bell crank lever 101 whose upper end is normally engaged by a latch 101 pivotally mounted upon the window frame of the window D. When the outer notched end of this latch is lowered it engages the upwardly extending arm of the bell crank lever 100 so that the rod 97 cannot shift under the action of the spring 98 and, therefore, cannot release the lever 96. When the lower sash of the window D is closed, however, a pin 102 is adapted to engage the latch 101 and lift it from its engagement with the lever 100, which will permit the rod 97 to shift and release the latches connected to the rods 19 so that 115 the sashes of the window F will close. This mechanism may also be used for the purpose of closing the windows in time of fire by the provision of a bell crank lever 103 having one end disposed beneath the outer 120

130

end of the latch 101, the outer end of the bell crank lever normally resting against a stop 104 and being held against this stop by a cord 105 which passes over pulleys and 5 is connected to a bell crank lever 106, one arm of which is weighted. This cord 105 may be any desired length and provided at a plurality of points with fusible connections 107. A spring 108 turns the bell crank 10 103 in a direction to lift the latch 101 when the cord 105 is burned or separated for any reason. This releases the lever 100 and causes the closing of the window F or the windows which may be connected to the 15 rod 97 in the manner that the window F is connected. An alarm of fire may also be sent in under these circumstances by providing a contact 109 on the bell crank lever 103 which, when the lever is turned, engages with the contact 110 which closes the 20 circuit through a fire alarm 111 located at any point, as for instance in a fire house or in the dwelling house itself.

As a means for throwing the lever 24 off 25 of its center when it is released by the armature 28, I provide a spring 24^a which contacts with the depending arm of the lever 24 and this spring is also connected by a wire 45 to the wire 44 of the main circuit 30 so that as soon as the armature 28 has been drawn over to release the arm 27 and release the window latches, the circuit through the battery will be broken, thus preventing the battery from becoming used up when for 35 instance the cup 35 is held down by water in the cap after the windows close. The connection 32 extends to an arm projecting upward from the lever 34 and should the electrical means for closing the windows fail, 40 the lever 31 will cause the operation of the armature 28 when the lever 34 drops under the weight of water. It will be obvious that this same operation may be manually performed if desired by pulling on the connection 32 or by manually depressing the lever 45 34 or by manually closing the main circuit through the magnet 30 by means of a switch. A bell 113 may also be mounted in this main circuit to ring or give any other signal 50 when the windows are automatically closed.

While I have illustrated in Fig. 1 a lever 18 formed with a rounded face 22, over which the cord 23 passes, it is to be understood that the lever might be straight, as in 55 Fig. 3.

In Figs. 4 and 6 I illustrate a modified form of window latch which may be used under certain circumstances and which is 60 particularly adapted to be used where the apparatus is installed within the walls of a house so as to be concealed from view. In this case there is no necessity of using the members 15 and 16 previously described but 65 the latches 121 are pivoted to the window

casing and either frictionally engage the edge of the sash or have protuberant portions at their free ends which engage with notches 122 formed in the window sashes. Each of the latches 121 is connected to the 70 corresponding rod 19 or 19^a and these in turn are connected to the lever 18^a which is adapted to place the latches under strain and tension the coiled resilient portion of the rods 19 and 19^a. In Fig. 4 is illustrated how 75 the operating cord 23 engages with the lever 18. It will be obvious that the operation of the form of latch shown in Figs. 4 and 6 is precisely the same as that shown in Fig. 2 in that a release of the strain upon the 80 rods 19 and 19^a will relieve the tension on the coiled portions of these rods and the latches 121 will no longer press inward with such strength against the window as to hold it but, on the other hand, will permit the 85 window to move downward either under its own weight or under the action of the spring roller 10. It is to be understood that in the construction shown in Figs. 1 and 2, the windows are held open by the engagement 90 of the relatively shallow notches of the latches 15 and 16 against the pins 13 and 14 and that because of the fact that the latches are held in operative position by the coiled portions 20 of the rods 19, the windows 95 may be shifted by hand with very little more exertion than is necessary to ordinarily raise or lower a window. The springs 20, however, when under tension are sufficient to hold the latches in engagement with the pins 13 and 14 but prevent the window from shifting by its own weight or under the action of the spring roller 10 or the ordinary sash weights. This is also true of Figs. 4 and 6 where the latches 121 100 will not prevent the manual shifting of the windows but will prevent the accidental shifting of the windows under the action of the spring roller or of the sash weights.

In place of the relatively long latching 110 member 16 with its plurality of notches 16^a, I may use a latching member 16^b, as illustrated in Fig. 7, this latching member 16^b being the same in form as the latching member 15 and having only one notch but in this 115 case the pin 14 will only engage with the latching member 16^b when the lower sash is fully raised and the window cannot be, therefore, adjusted at various heights.

It will be seen that the magnet 30 is connected by the wire 45^a to the lever 24 and that this lever is normally connected through the spring 24^a to the wire 45 which extends to one pole of the battery while the other side of the magnet 30 is connected by the 125 wire 45^b to the wire 43 or the other wires which complete the circuit to the other pole of the battery.

The general operation is obvious from what has gone before. The circuit leading 130

through the magnet 30 is open at all times unless one of the automatic circuit closing devices is actuated, whereupon the circuit through the magnet 30 is closed, the magnet 5 is energized, the member 24 is released and rotates upon its pivot, thus relieving the strain on the lever 18, this in turn relieving the strain on the springs 20 and releasing the pressure on the sash latches so that the 10 sashes will close. It will be seen from Fig. 1 that each automatic releasing device or circuit closer is independent of any other circuit closer and that under any of the varying conditions named the windows will close.

15 I do not wish to be limited to the specific constructions illustrated as it is obvious that these may be modified in many ways without departing from the spirit of the invention and that while all of the circuit closing devices 20 may be used with a window or series of windows, yet only one need be used if it be only desired to close the windows under one certain condition.

Thus it is to be understood that while I have shown the casing E with the magnetic latch therein as being disposed below the windows, there would be occasions where it will be best that the magnetic latch be disposed above the windows or such a distance 30 above the ground that it could not be accidentally or maliciously operated.

Having described my invention, what I claim is:

1. The combination with a sliding window sash urged to a closed position, of means for holding the sash in a shifted position comprising a latch operatively engaging with the sash, a lever pivoted adjacent the sash, a pull connection attached to the lever and 35 including a coiled contractile spring, said connection when under strain causing the latch to operatively engage the sash, means for rotating said lever to a position to apply strain on the pull connection, means for holding said lever in its last named position, and means for releasing the holding means to thereby slacken the tension of the spring.

2. The combination with a pair of windows each having sliding sashes urged to a 50 closed position, of a pair of latches coacting with the upper and lower sashes of each window, a rotatable member disposed between the windows, pull connections extending from said latches to opposite ends of 55 said rotatable member and each including a coiled spring, and means for rotating said member in one direction to a position to tension the spring or rotate said member in the other direction to a position to relieve the 60 tension on the spring to thus relieve the operative engagement between the latches and the sashes.

3. The combination with a window having sashes urged to a closed position, of latches 65 one for each sash, a lever pivoted adjacent

the sash, pull connections attached to the lever and each latch, each pull connection including a coiled resilient section, the lever when turned in one position tightening the pull connections and increasing the tension 70 of the spring sections whereby to hold the latches in operative engagement with the sashes, means for holding the first named lever in operative position comprising a bell crank lever, a flexible connection between the bell crank lever and the first named lever, said bell crank lever when turned to one position tightening said flexible connection and holding the first named lever from release, a detent armature spring actuated to engage 75 the arm of the bell crank lever and hold it in its holding position, a magnet adapted to attract the armature and release said holding lever, said magnet being disposed in a normally open circuit with a source of energy, 80 automatically operated means for closing said circuit, and mechanically operated means for shifting said armature out of engagement with the arm of the bell crank lever. 90

4. The combination with a window casing and sash, the latter being urged in one direction, of means for holding the sash in shifted position comprising a latching member pivoted on the window casing and operatively engaging the sash, a coiled contractile spring attached to said latching member, a pivoted member to which the coiled spring is operatively connected, the pivoted member applying strain to the spring and latch 100 when it is disposed in one position, and releasable means for holding the pivoted member in applied position. 95

5. The combination with a window casing and sash the latter being urged in one direction, of means for holding the sash in shifted position comprising a latching member pivoted on the window casing and operatively engaging the sash, a coiled contractile spring connected at one end to the latching member, a pivoted member to which the other end of the spring is connected to one side of the pivot of said member, whereby when said member is turned to a predetermined position it will apply strain to the 110 spring and to the latch, and releasable means for holding said strain applying member in its strain applying position. 115

6. The combination with a window casing and a sash urged in one direction, of means 120 for holding the sash in shifted position including a pivoted latching member on the window casing operatively engaging the sash, a coiled contractile spring engaged at one end with said latch and when under 125 strain urging the latch to an operative position, means for holding said spring under tension including a pivoted member rotatable in one direction to apply strain to the spring and in the other direction to relieve 130

said strain, and means for holding said member in a strain applying position including a detent, a co-acting electro-magnet which when energized will shift the detent 5 to releasing position, a source of current connected in an interrupted circuit with said electro-magnet, and means for closing the circuit through the magnet.

7. The combination with a window latch, 10 including a pull member operatively engaged with one end of the latch, and means for holding the latch in operative position and applying strain to the pull member including a pivoted member rotatable in one 15 direction to apply strain to the pull member and in the other direction to release said strain, a spring urging the pivoted member in a direction to relieve the strain, a detent holding the pivoted member from moving 20 to its releasing position, and a coacting electro-magnet operatively engaging the detent to cause the release of said detent when the magnet is energized, the magnet being connected in a normally open circuit with a 25 source of current, and means for closing said circuit.

8. The combination with a window casing and an upper and a lower sash, both of said sashes being urged to a closed position, of 30 means for holding the sashes in shifted position comprising a latching member for the lower sash pivoted to the window casing and extending for a distance along the window casing and provided with a plurality of

notches, a pin on the lower sash engageable 35 with any one of said notches, a latching member pivoted upon the window casing and coacting with the upper sash and having a notch, a plurality of pins on the upper sash any one of which is engageable with 40 the notch, means for yieldingly urging said latches into engagement with said pins, and releasable means for normally holding the latches in operative position.

9. The combination with a window casing 45 and a sash, the sash being urged in one direction, of means for holding the sash in shifted position against the action of said urging means comprising a latching member pivoted on the window casing and a co-acting member on the sash, one of said members having a relatively shallow notch into which the other member engages, a spring which, under tension, urges the members 50 into engagement with each other, a connection attached to the spring and when under strain increases the tension of the spring and the strength of engagement between said members, and manually releasable means for holding the connection under strain.

In testimony whereof I hereunto affix my signature in the presence of two witnesses.

LEONARD M. PHELPS.
